UNITED STATES PATENT OFFICE.

WILLIAM DRISCOLL, OF TAUNTON, MASSACHUSETTS, ASSIGNOR TO HIMSELF
AND HENRY D. ATWOOD, OF SAME PLACE.

MECHANISM FOR FINISHING STOPPERS FOR STEEL LADLES.

SPECIFICATION forming part of Letters Patent No. 248,721, dated October 25, 1881.

Application filed April 7, 1881. (No model.)

To all whom it may concern:

Be it known that I, WILLIAM DRISCOLL, of Taunton, in the county of Bristol and State of Massachusetts, have invented a new and useful Improvement in Mechanism for Finishing Stoppers for Steel Ladles, of which the following is a specification.

Figure 1 is a sectional side elevation of a part of my improvement and of a stopper placed upon it. Fig. 2 is a side elevation, partly in section, of another part of the improvement. Fig. 3 is a plan view of the part of the improvement shown in Fig. 1. Fig. 4 is a plan view of both parts of the improvement, illustrating their use.

Similar letters of reference indicate corresponding parts.

The object of this invention is to facilitate the finishing of stoppers for steel ladles and other uses.

The invention consists in constructing a mechanism for finishing stoppers for steel ladles, with a block having a recess to receive, fit upon, and smooth the concaved head of the stopper, a pin to pack and smooth the inner surface of the bore of the stopper, and a lever having a socket to receive the center pin, and a slot to receive the knife, and its set-screw for rabbeting the base of the stopper, all constructed and operating as will be hereinafter fully described.

A represents a block of wood, metal, or other suitable material, and which has a screw-hole formed in its base, or in a projection formed upon its base, to receive the screw that secures it to a potter's wheel or other revolving wheel or table.

In the upper side of the block A is formed a cup-shaped recess or cavity, B, of such a size and shape as to receive and fit upon the concaved or rounded end of a stopper, C, as shown in Fig. 1.

To the block A, in the center of its recess B, is secured by a screw, D, the base of a pin, E, which has a shoulder, F, upon its lower part to receive the shoulder in the base of the stopper C, as shown in Fig. 1. The enlarged lower part of the pin E is made smaller than the enlarged forward part of the bore of the stop-

per C. The smaller upper part of the pin E is 50 made of the exact size of the required bore of the stopper. With this construction, when the stopper C has been brought to the proper shape and size, the bore formed through it, and the enlargement in the forward end of the bore 55 formed in the ordinary manner, the stopper C is placed upon the pin E, with the head of the said stopper resting in the recess B of the block A. By this operation the revolving pin E packs and smooths and thus finishes the inner surface of the bore of the stopper C, and the concaved surface of the block A packs and smooths and thus finishes the concaved surface of the head of the said stopper.

With careful manipulation the recessed block 65 A and the pin E can be used separately; but I prefer to use them together, as in this way the operator can more readily keep the various parts of the stopper exactly true.

To form the rabbet in the base of the stopper C the tool shown in Fig. 2 is used, which consists of the lever G and knife H. The lever G has a socket, I, formed in its end to receive and fit upon the projecting end of the pin E.

In the lever G, at a suitable distance from the socket I, is formed a slot, J, to receive the knife H, which is secured in place by a set-screw, K, passing in through a screw-hole in the rear side of the lever G, and resting against 75 the rear side of the knife H. The forward end of the knife H is made square and at right angles with the length of the said knife. The forward end of the inner edge of the knife H is beveled, as shown in Fig. 2, to give the desired bevel to the shoulder of the stopper C. The part of the lever G in front of the middle part of the knife H is cut away to allow the chips to escape freely.

The slot J should be made a little longer 90 than the width of the knife H, to allow the knife to be conveniently adjusted.

Having thus fully described my invention, I claim as new and desire to secure by Letters Patent—

1. A mechanism for finishing stoppers for steel ladles, constructed substantially as herein shown and described, consisting of the block

A, having recess B, the pin E, having shoulder F, the lever G, having socket I and slot J, the knife H, and the set-screw K, as set forth.

2. In a mechanism for finishing stoppers for steel ladles, the pin E, constructed, substantially as herein shown and described, with a shoulder, F, to receive the shoulder in the bore of the stopper, whereby the inner surface of the bore of the stopper is packed and smoothed, to as set forth.

3. In a mechanism for finishing stoppers for steel ladles, the combination, with the lever G, having socket I and slot J, of the knife H and set-screw K, substantially as herein shown and described, whereby a rabbet can be formed in the base of the stopper, as set forth.

WILLIAM DRISCOLL.
